UNITED STATES PATENT OFFICE.

THOMAS E. PRAY, OF CHICAGO, ILLINOIS, ASSIGNOR TO GOODMAN MANUFACTURING COMPANY, OF CHICAGO, ILLINOIS, A CORPORATION OF ILLINOIS.

CUTTER CHAIN.

Application filed June 16, 1923. Serial No. 645,762.

To all whom it may concern:

Be it known that I, THOMAS E. PRAY, a citizen of the United States, residing at Chicago, in the county of Cook and State 5 of Illinois, have invented new and useful Improvements in Cutter Chains, of which the following is a specification.

This invention relates to improvements in cutter chains for mining machines and has 10 for its principal object to provide a simple and durable construction of chain block and cutter bit.

More specifically, the object of my invention is to provide an improved construction 15 and arrangement of clamping means for the cutter bit in a block of the type disclosed in my prior applications bearing Serial Number 431,250, filed December 16, 1920, and Number 600,499, filed November 20 13, 1922, with particular reference to the clamping device for the bit.

The invention may be best understood by reference to the accompanying drawings in which:

25 Figure 1 is a side view of a chain block with the bit in place.

Figure 2 is an end view of the chain showing it in position in a cutter head of a mining machine.

30 Figure 3 is a perspective view of an improved bit gripping element forming a part of my invention.

Figure 4 is a detail view of the clamping element for the bit with a portion thereof broken away.

In the drawings I have shown a cutter chain for mining machines which is made up of a series of chain blocks 1, 1, pivotally connected together by a series of suitable straps 2, 2. The chain in use is an 40 endless chain that passes about a driving sprocket and works in a grooved cutter head 7. The cutter head is preferably provided at the top and bottom with guideways 3, 3, in which the restraining lips 4 and 5 on 45 the blocks and straps are retained. The blocks are provided with cutter bits 6, 6. The cutter chain is made up of a series of such chain blocks which extend at various 50 angles from the grooved cutter head, as shown in Figure 2.

The cutter bit 6 is preferably of flat bar stock having a substantially uniform cross-section intermediate its ends and is inclined

forwardly and outwardly in a bit receiving 55 aperture 9, formed in the body of the block.

Means for securing the bit in the block comprise a clamping member 14 which fits in an aperture 15 extending lengthwise through the outer portion of the block at 60 substantially right angles to the bit 6. This aperture is preferably made of substantially uniform cross-section throughout its length, as for example, it may be a drilled hole in which the clamping member 14 is 65 fitted. In the form shown in the drawings, the forward end of the clamping member 14 is adapted to extend through and be substantially flush with the forward face 8 of the block, as is disclosed in my co-pending 70 application bearing Serial Number 600,499, although my present invention does not relate to this feature, and the clamping member 14 may also stop short of the forward face 8 of the block, as in the form 75 disclosed in another co-pending application bearing Serial Number 431,250.

The specific feature of novelty forming the subject matter of the present invention relates to the provision of a gripping device 80 to be used in conjunction with a clamping member 14 so as to securely hold the bit 6 in place in the block. One of the difficulties in the operation of cutter chains having removable bits therein is that of securing the bits in the blocks so that they 85 cannot work loose while in operation. The clamping pressures which may be exerted by screw devices of the ordinary kinds have not been satisfactory for this purpose where 90 the engaging surface of the clamping device is a plane surface. It therefore has been found necessary in devices of this character to provide a gripping device preferably of relatively hard material, such as tool 95 steel, having roughened surfaces adapted to afford a firm grip upon the bit. In the present invention I provide an improved form of gripping device comprising a threaded member 20, preferably of special 100 steel, heat treated to a high degree of hardness. A suitable slot 21 of the usual kind may be formed in the threaded member 20, as shown. This gripping device is screwed 105 into the clamping member 14 at the forward end of the bit receiving aperture or recess 16. This aperture 16 is adapted to be positioned in alignment with the bit re-

ceiving aperture 9 in the block, so as to receive the bit 6 therethrough. The gripping member 20 is screwed into the clamping member so that its axis will be parallel to the front surface of the bit with which it is to be engaged. The rearmost threaded portion of the gripping member is arranged to extend into the recess 16 as shown in Figure 4.

10 The rear end of the clamping member is provided with a threaded portion 18 adapted to extend beyond the rear face of the block and having a nut 19 thereon. Means are provided for preventing the rotation of the 15 clamping member, such as a pin 22 extending through the block and engaging a flattened surface 23 formed on the clamping member. The pin 22 is also adapted to engage a shoulder 24 on the clamping member 20 to retain the latter in the block.

In the improved form herein disclosed it will be seen that the clamping member 14 is provided with an extremely simple form 25 of gripping device which may be readily made up from threaded material and easily assembled in the clamping member. Threads provide the necessary grip to the bit along the entire length of the gripping device and being of relatively hard material 30 effectively resist wear incident to it. However, as the threads become worn the gripping member may be rotated either in one direction or the other so as to present a new gripping surface to the bit thereby providing several changes in the operating surface 35 with the simplest kind of an adjustment, and without necessitating replacement of the gripping device. In the form shown, adjustment of the gripping device may be made without removing the clamping member 14 from the block by simply loosening and withdrawing the bit 6 from its aperture 9 and then by shifting the clamping device to the rear, it may be brought into

45 position where a screwdriver may be inserted through the bit-receiving aperture 9 to engage the gripping member 20 and rotate it.

I claim as my invention:

1. In combination with a cutter chain 50 block for mining machines having a bit receiving aperture therein, a bit, a clamping member arranged transversely of said bit receiving aperture and having means adjustable from the rear end of said block for drawing said clamping member rearwardly 55 to secure the bit in bearing engagement in said bit receiving aperture, and a bit gripping device comprising a plug of relatively hard material threaded transversely in said clamping member with the threaded portion 60 along one side in position to engage the bit.

2. In combination with a cutter chain 65 block for mining machines having a bit receiving aperture therein, a bit, a clamping member arranged transversely of said bit receiving aperture and having means adjustable from the rear end of said block for drawing said clamping member rearwardly 70 to secure the bit in bearing engagement in said bit receiving aperture, a bit gripping device comprising a plug of relatively hard material threaded transversely in said clamping member with the threaded portion 75 along one side in position to engage the bit, and means securing said clamping member for limited longitudinal movement in said block, said last named means affording rearward movement of the clamping member into position to permit rotational adjustment of said plug by the insertion of a tool through the bit receiving aperture 80 when the bit is removed therefrom.

Signed in Chicago, in the county of Cook 85 and State of Illinois, this 11th day of June, 1923.

THOMAS E. PRAY.
